(57) **CLAIM**

The ornamental design for a hood mounted mirror for a truck, as shown and described.

DESCRIPTION

FIG. 1 is a perspective view of a left hand embodiment of a hood mounted mirror for a truck showing our new design; FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a hood mounted mirror of our new design;

FIG. 9 is a perspective view of a right hand embodiment of a hood mounted mirror for a truck showing our new design;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 is a perspective view of a hood mounted mirror of our design.

In the drawings, the broken lines in the drawings depict portions of the design and a truck body that form no part of the claimed design.
